Patented Mar. 28, 1911.

UNITED STATES PATENT OFFICE.

CHARLES SPIRO, OF NEW YORK, N. Y.

BACK-SPACING MECHANISM.

987,761.

Specification of Letters Patent. Patented Mar. 28, 1911.

Application filed July 26, 1910. Serial No. 573,862.

To all whom it may concern:

Be it known that I, CHARLES SPIRO, a citizen of the United States, residing at New York, county of New York, State of New York, have invented certain new and useful 5 Improvements in Back-Spacing Mechanism, of which the following is a specification, reference being had therein to the accompanying drawing.

0 This invention relates broadly to the art of typewriting machines and specifically to back spacing mechanisms wherein the carriage of the typewriter is adapted to be moved step-by-step in a direction opposite 15 to the movement of the carriage when under the influence of the letter spacing mechanisms.

The principal object of the invention is to provide an efficient back spacing mechanism 20 with a minimum number of operative parts.

Another object of the invention is to provide a back spacing mechanism in which the back spacing dog is substantially locked in engagement with the back spacing rack 25 when the dog has substantially reached its limit of travel during the back spacing movement.

A further object of this invention is to provide an adjustable stop, by means of 30 which the normal amount of movement of the back spacing dog may be predetermined.

A further object of this invention is to construct a back spacing mechanism in 35 which the rack engaging dog is formed integral with the carrying link therefor.

A further object of this invention is to construct a back spacing mechanism in which the back spacing dog may be resiliently held in engagement with the back 40 spacing rack.

A further object of this invention is to construct a back spacing mechanism in such manner that the back spacing dog will immediately leave the back spacing rack as 45 soon as the pressure is relieved upon the back space key.

A still further object of this invention is to construct a back spacing mechanism in such manner that the back spacing dog may 50 automatically adjust its engaging teeth to the position of the back spacing rack in order that the engaging parts may not be injured by being forced into abnormal positive engagement with each other.

55 Other objects of the invention will in part be obvious and will in part be pointed out in

the specification hereinafter following, by reference to the accompanying drawings which form a part thereof, and the scope of the invention will be indicated by the appended claims.

Throughout the several figures of the drawings like numerals are used to indicate like parts.

Figure 1 is a plan view of the back spacing mechanism. Fig. 2 is a view showing the mechanism in Fig. 1 in elevation. Fig. 3 is a view showing the back spacing dog in elevation in its relation to the back spacing rack. Fig. 4 is a detail plan view of the back spacing dog. Fig. 5 is a detail view showing the back spacing dog in elevation. Fig. 6 is a plan view of the adjustable stop. Fig. 7 is a view showing the adjustable stop in elevation.

As this invention is restricted specifically to back spacing mechanism for typewriting machines, the back spacing mechanism only, has been illustrated. The other portions of the typewriting machine which are well known in the art are omitted from the drawings, with the exception of certain portions of the machine frame, which have been indicated by dotted lines.

Referring specifically to Figs. 1 and 2 of the drawings, a back spacing lever 1 is provided on its forward end with a finger or thumb piece 2, and is pivoted to the machine frame 3, by means of a pivot member 4. The rear end of the back spacing lever 1, is adapted to be connected with a longitudinally moving link dog carrier 5 by means of a pivot stud screw 6. The pivotal joint formed by means of the stud screw 6, is of such a nature as to allow the link dog carrier 5 a limited amount of movement in a vertical direction, for a purpose which will hereinafter be more specifically described. The link dog carrier 5, comprises a longitudinal portion 7, which is offset in order to provide a sufficient expanse of metal from which to cut the controlling slot 9.

The outer end of the link dog carrier is formed with a raised curved portion 10, which is provided with a toothed head 11, 10, the teeth of which are adapted to conform and mesh with teeth formed upon a back spacing rack 12. The back spacing rack 12, may be an independent rack adapted for the purpose of back spacing only, or it 110 may be the rack which is engaged by the escapement dogs for controlling the for-

ward letter spacing. However, the structure specifically illustrated in the drawings refers to a rack which is independent of the usual rack engaged by the escapement 5 dogs which controls the carriage in its letter spacing movement.

The slot 9 is formed at its outer end into a downwardly curved portion 14, which meets the parallel upper and lower sides 15 and 16 of the slot. A carriage top plate 3 of the machine, is provided with a downwardly depending bracket 17, which forms a carrying support for a stud screw 18, that is adapted to pass through the controlling 15 slot 9 in the dog carrying link 5. A reTRACTING COILED SPRING 19, is attached to a pin 20 on the dog carrier 5, and a similar pin 21 on the lower part of the top plate 3, in such manner that the dog carrier 5 is normally retracted to a position wherein the stud screw 18 occupies the position in the controlling slot that is illustrated in Fig. 3. An adjustable stop member 22, is formed with elongated openings 24 and 25, 25 through which binding screws 26 and 27 are adapted to pass, and clamp the adjustable stop member in a predetermined fixed position upon the side of the link dog carrier 5. The outer end of the adjustable 30 stop member 22, is curved as at 28, in such manner that the upper portion of the curve overhangs to a slight degree the lower portion of the curve. The curve face 28 is adapted to engage with the stud screw 18 35 when the dog carrier has reached its limit of travel, and the overhanging upper portion of the curve 28 is constructed to so fit over the stud screw 18 as to substantially lock the toothed head 11 in firm engagement with the teeth of the back spacing rack 12, in order to prevent any overthrow 40 of the carriage when the back spacing mechanism is violently actuated.

The operation of the device is substantially as follows:—As the thumb piece 2, of the back spacing lever 1, is pushed in an outward direction, the back spacing lever is swung upon its pivot 4, and the moving dog carrier 5, is given a longitudinal 50 movement in a direction opposite to the normal movement of the typewriter carriage when moving under the influence of the usual carriage spring drum (not illustrated). The link dog carrier at this time 55 is under the influence of two forces, *i. e.*, the force on the finger key tending to move the dog carrier forward, and the force of the retracted spring 19 tending to pull the dog carrier upward. The result of these 60 forces is to cause the stud screw 18 to ride downward over the curved wall 14, of the slot 9, in such manner that the toothed head 11 comes into engagement with the teeth on the back spacing rack 12. It will be 65 noted that one of the forces tending to

bring these engaging teeth together, is that of the coiled spring 19, and therefore if the teeth on the rack 12 are not in a proper position to engage the toothed head 11, the engaging teeth on the head immediately 70 yield sufficiently to prevent the binding action which frequently occurs wherein back spacing mechanisms are arranged to drive the back spacing dog into positive engagement with the back spacing rack. After 75 the head 11 has engaged the back spacing rack, the carriage to which this rack is attached, is forced to move under the influence of finger pressure until the curved face 28, on the adjustable stop member 22, comes 80 into engagement with the stud screw 18, at which time the teeth on the head 11 are positively cammed or locked in engagement with the teeth on the rack 12, because of the wedging action due to the overhanging portion of the curved face in its engagement with the head of the stud screw 18. Immediately as pressure is released 85 from the finger key, one of the component forces which has been holding the head 11 90 in engagement with the rack 12, disappears, and the engaging head immediately drops away from the rack and the several parts are returned to their normal position, due to the influence of the retracted spring 19. 95

Having thus described my invention what I desire to claim as new and secure by Letters Patent is:—

1. In a back spacing mechanism for a typewriting machine, the combination of an operating lever, a dog carrying link, means operatively connecting said operating lever with said dog carrying link, a back spacing dog carried by said dog carrying link, a back spacing rack, resilient means for causing said back spacing dog to engage said back spacing rack; an adjustable stop member carried by said dog carrying link, and means co-operating with said adjustable stop member to lock said dog in engagement with said rack. 100

2. In a back spacing mechanism for a typewriting machine, the combination of an operating lever, a link, means operatively connecting said lever with said link, a back spacing dog carried by said link, a back spacing rack, resilient means for causing said back spacing dog to engage said back spacing rack, and adjustable means for limiting the extent of movement of said back spacing dog and locking said dog in engagement with said rack only at the end of its spacing movement. 115

3. In a back spacing mechanism for a typewriting machine, the combination of an operating lever with a link, a dog carried by said link, a back spacing rack, resilient means for causing said dog to engage with said back spacing rack, and adjustable means carried by said dog for locking it in engage- 120 125 130

ment with said rack at the end of the travel of said dog toward the rack.

4. In a back spacing mechanism for a typewriting machine, the combination of an operating lever, with a dog carrying link, pivotal means connecting said lever to said link, a back spacing dog formed integral with said back spacing link, said back spacing link being formed with a slot having 10 one wall curved, a guiding stud adapted to coöperate with the walls of said slot, a spring member for holding the walls of said slot in engagement with said stud, a back spacing rack, the arrangement and construction of parts being such that the back spacing dog is resiliently thrown into contact with said back spacing rack when the operating lever is actuated.

5. In a back spacing mechanism for a typewriting machine, the combination of an operating lever, a dog carrying link, pivotal means for attaching said operating lever to said dog carrying link, a back spacing dog carried by said dog carrying link, said dog carrying link being provided with a slot, one wall of which is curved, a guiding stud of less diameter than the width of said slot, and adapted to engage one wall of said slot, 20 a back spacing rack, a resilient member 25 having one end connected to said dog carrying link in such manner as to cause said back spacing dog to engage said back spacing rack when said operating lever is actuated, and an adjustable stop member adapted 30 to limit the degree of movement of said back spacing dog carrier.

6. In a back spacing mechanism for a

typewriting machine, the combination of an operating lever, a dog carrying link, pivotal means for attaching said operating lever to 40 said dog carrying link, a back spacing dog formed integral with said link, a rack, a portion of said dog carrying link being formed with a curved wall, means coöperating with said curved wall to guide the direction of movement of said link, and resilient means for maintaining said curved wall in contact with said guiding means during the actuation of said back spacing mechanism. 50

7. In a back spacing mechanism for a typewriting machine, the combination of an operating lever, with a dog carrying link, means operatively connecting said dog carrying link to said operating lever, a back 55 spacing dog carried by said dog carrying link, a back spacing rack, said link being formed with a curved guide wall portion, guiding means adapted to contact with said curved wall, means for maintaining said 60 curved wall in contact with said guiding means, and a wedged-shaped cam member constructed in such manner as to cause said back spacing dog to be substantially locked in engagement with said back spacing rack 65 when said dog carrying link has reached its limit of travel in its back spacing movement.

In testimony whereof I affix my signature in presence of two witnesses.

CHARLES SPIRO.
